UNITED STATES PATENT OFFICE.

LEONARD CHARLES BYGRAVE AND THOMAS MONTAGU INMAN, OF LONDON, ENGLAND,
ASSIGNORS TO THE RELAY AUTOMATIC TELEPHONE COMPANY, LIMITED, OF LON-
DON, ENGLAND.

TELEPHONE SYSTEM.

1,342,792.

Specification of Letters Patent.

Patented June 8, 1920.

Application filed July 25, 1917. Serial No. 182,670.

To all whom it may concern:

Be it known that we, LEONARD CHARLES BYGRAVE and THOMAS MONTAGU INMAN, subjects of the King of Great Britain, and 5 residents of Marconi House, Strand, London, England, have invented a new and useful Improvement in Telephone Systems, of which the following is a specification.

This invention refers to automatic and 10 semi-automatic telephone systems having a three digit final connecting group, and particularly to the final connecting stage thereof.

Owing to the economy and efficiency of 15 grouping trunk lines in large groups, attempts have been made to use larger switches than those for 100 and 200 subscribers' lines, which are well known, but owing to cost and complexity these have 20 not been adopted. This invention, however, provides a simple and economical means of giving a group of trunk lines access to large groups of subscribers, and the invention is described in connection with access to 25 groups of 1000 lines. Such a large group must necessarily be associated with 3-digit calling, hundreds, tens and units, and preferably a plurality of common 3-digit impulse responders or selectors is provided to 30 receive the dial impulses and complete initial energizing circuits in sub-groups to correspond with the digits called, but these responders form no part of this invention. In a 10,000 line system the subscriber's calling line may be arranged in any well known 35 manner, for example, as in United States Patent No. 1234610, these lines having access by preselectors or line switches to first selector switches which extend a calling line 40 on the first set of digit impulses to a particular group of 1000 lines, for example, as in United States Patents Nos. 1162556 and 1195771. Our invention relates to switching devices involved in the subsequent comple- 45 tion of the connection in response to hundreds, tens and units impulses transmitted by the caller to connect his line with a particular line desired. The common impulse responding device and initially energizing arrangements for selecting one line in a group of 1000 may be such as described in United States Patent No. 1129543.

Figure 1 of the drawings is a schematic diagram illustrating the invention and Fig.

2 is a circuit diagram which, for the sake 55 of simplicity, is restricted to those parts only of Fig. 1 which are shown in heavy lines.

As shown in Fig. 1, a connection is completed over a succession of small switching 60 units. Connecting circuits are indicated by single lines, and the connecting points are indicated by X's at the intersections of lines. The group of trunks necessary to carry the traffic to the group of subscribers is divided 65 into a number of sub-groups, and three sets of intermediate lines, which may be known as first, second and third intermediate lines, have each a similar number of sub-groups, and a circuit in each sub-group is joined 70 together to complete a connection.

Each line of a trunk sub-group *a*, *b*, *c* or *d*, has access to all the lines in a sub-group of first intermediate lines *a'*, *b'*, *c'* or *d'*. Each first intermediate line has access 75 to one line in each sub-group of second intermediate lines *a''*, *b''*, *c''*, *d''*, and each line in each sub-group of second intermediate lines has access to all the lines of a sub-group of third intermediate lines *a'''*, *b'''*, *c'''* 80 or *d'''*.

A group of subscribers' lines that may be called is shown at s 1, 2, 3, 4, 5, each subscriber's line being capable of connecting with six intermediate lines *a⁴*, *a⁵*, *b⁴*, *c⁴*, *c⁵*, *d⁴*, which are extensions of the third intermediate lines *a'''*, *b'''*, *c'''*, *d'''*. The six intermediate lines to which any subscriber's line has access may be connected to the third intermediate lines as best suits traffic re- 90 quirements. By such an arrangement of lines, it is possible for any incoming trunk in sub-groups *a*, *b*, *c*, *d*, to connect with any subscriber's lines in a group of 1000 lines, such as s 1, 2, 3, 4, 5. 95

Fig. 2 shows the operating circuits for such a system. For the simplification of the diagram only the third conductors are shown. The connecting relays would, of course, carry the usual two line wires of the 100 talking circuit.

Only two sub-groups of trunks and intermediate lines are shown in Fig. 2, the trunk groups being *A*, *B*; the first intermediate line groups *A'*, *B'*; the second intermediate line groups *A''*, *B''*; and the third *A'''*, *B'''*; the intermediate lines extended to subscribers' units *A⁴*, *A⁵* and *B⁴*. The sub-

scribers' lines are shown at S^1 , S^2 , S^3 . When a subscriber in a group of 1000 lines is called, the apparatus that responds to the dial impulses energizes, and directly, or 5 through interposed apparatus, completes initial energizing circuits. In Fig. 2 it is assumed that four circuits have been completed or partly completed in this way.

Circuit 1 is completed to connect the common side of all relays e to earth, so that they 10 energize. A relay e is associated with each first intermediate line of the sub-group A' . If all lines of a sub-group are idle, all relays e of that sub-group energize.

Circuit 2 is completed to energize the incoming test relay f of the sub-group of subscribers. This connects the third conductors of certain third intermediate lines to the test relays g of the subscribers' sub- 20 group.

Circuit 3 has battery connected to the free wire of S^1 (if that subscriber is called) so that when a test relay g energizes, the corresponding connecting relay h will energize.

Circuit 4 has earth connected to the free wire of the trunk over which a call is being made, so that a connecting relay i may be energized when relays e and a particular relay j have energized to find an idle intermediate line. The relays e when energized each connect a wire in each sub-group of first intermediate lines to a relay j and battery.

Circuit 5 is completed and relays k' , m^2 , 35 n' and g' energize. k' momentarily opens the circuit of other relays k to prevent interference. j' energizing completes circuit 4 so that the connecting relay i' is energized to connect the calling trunk to a first intermediate line A' .

Circuit 6: j' and k' energizing complete a circuit in which the connecting relay o' is initially energized to extend a line A' to a second intermediate line A^2 .

Circuit 7: k' and m^2 energizing complete a circuit in which the connecting relay p' is initially energized to extend a line A^2 to a third intermediate line A^3 . Relay g' energizing completes circuit 3 to cause the connecting relay h' to extend the line A^3 to the wanted subscriber's line S' .

Circuit 8 is the retaining or holding circuit of the completed connection, in which connecting relays i' , o' , p' , h' , are maintained energized; the cut-off relays q' , r' , t^2 , u' , v' are energized and maintained with relay n' which cuts in relay u' . q' causes e' and j' to deenergize to open the initial energizing circuits of relays i and also the circuits 5 and 6. r' energizing cuts off h' so that a second call in the same sub-group will energize k^2 . t^2 energizing opens the test circuit 5, so that the circuit tests busy when relays g are connected up by f . u' energizing 65 cuts off g' so that g^2 is taken for the next

call. v' is the cut-off relay of the called party's line.

The same calling trunk can obtain connection with the same party by any of the sub-groups of intermediate lines, as pointed out in connection with Fig. 1. The calling trunk, in the connection described, can initiate a connection through any of the relays e ; each relay e can extend the connection to any intermediate line of its particular sub-group, and the latter in conjunction with the testing device associated with the called subscriber's line sub-group will select a particular third intermediate line to be connected with the called party.

What we claim is:

1. In an automatic telephone system having a final connecting group adapted to be operated by more than two digits, the combination of a group of trunks, a group of 85 subscribers' lines, a plurality of greater than two of sets of intermediate lines arranged with the sets in series between the trunks and subscribers' lines in the final connecting group and means for connecting a trunk to 90 a subscriber's line through lines of all the sets in series.

2. In an automatic telephone system having a final connecting group adapted to be operated by more than two digits, the combination of a group of trunks, a group of subscribers' lines, a plurality greater than two of sets of intermediate lines arranged with the sets in series between the trunks and subscribers' lines in the final connecting group and means for connecting a trunk to a subscriber's line through lines of all the sets in series, no intermediate line being capable of being taken into engagement unless it can form part of a completed connection.

3. In an automatic telephone system having a final connecting group adapted to be operated by more than two digits, the combination of a group of trunks, a group of subscribers' lines, a plurality greater than 110 two of sets of intermediate lines arranged with the sets in series between the trunks and subscribers' lines in the final connecting group and means for connecting a trunk to a subscriber's line through lines of all the sets in series in which only those connecting means by which a through connection can be completed are operable.

4. In an automatic telephone system having a three digit final connecting group, the 120 combination of a group of trunks, a group of subscribers' lines, a plurality greater than two of sets of intermediate lines arranged with the sets in series between the trunks and subscribers' lines and means for connecting a trunk to a subscriber's line through lines of all the sets in series in which the connecting means between the various intermediate lines concerned in a connection are 125 all operated simultaneously.

5. In an automatic telephone system having a final connecting group adapted to be operated by more than two digits, the combination of a group of trunks, a group of subscribers' lines, a plurality greater than two of sets of intermediate lines arranged with the sets in series between the trunks and subscribers' lines in the final connecting group, means for connecting a trunk to a subscriber's line through lines of all the sets in series and a temporary testing circuit adapted to cause the connecting means to be operated if the connection can be completed through them.
- 10 6. In an automatic telephone system having a three digit final connecting group, the combination of a group of trunks, a set of first intermediate lines divided into sub-groups, means for connecting any trunk to any one of the first intermediate lines of a sub-group, a set of second intermediate lines divided into sub-groups, means for connecting any first intermediate line to a line of any one sub-group of second intermediate lines,
- 15 25 a set of third intermediate lines divided into sub-groups, means for connecting any second intermediate line to any of the third intermediate lines of a sub-group and a group of subscribers' lines, each subscriber's line having access to one line of each of a plurality of the sub-groups of third intermediate lines and means for initially completing two temporary circuits to establish connection between a calling line and a called line.
- 20 30 7. In an automatic telephone system having a three digit final connecting group, the combination of a group of trunks, a set of first intermediate lines divided into sub-groups, means for connecting any trunk to any one of the first intermediate lines of a sub-group, a set of second intermediate lines divided into sub-groups, means for connecting any first intermediate line to a line of any one sub-group of second intermediate lines,
- 35 40 45 50 75 80 85 90 95
- the third intermediate lines of a sub-group, a group of subscribers' lines, each subscriber's line having access to one line of each of a plurality of the sub-groups of third intermediate lines and means for rendering inaccessible any intermediate line incapable of forming part of a particular connection between a trunk and a subscriber's line.
8. In an automatic telephone system having a three digit final connecting group, the combination of a group of trunks, a set of first intermediate lines divided into sub-groups, means for connecting any trunk to any one of the first intermediate lines of a sub-group, a set of second intermediate lines divided into sub-groups, means for connecting any first intermediate line to a line of any one sub-group of second intermediate lines, a set of third intermediate lines divided into sub-groups, means for connecting any second intermediate line to any one of the third intermediate lines of a sub-group, a group of subscribers' lines, each subscriber's line having access to one line of each of a plurality of the sub-groups of third intermediate lines and means for initially completing two temporary circuits to establish connection between a calling line and a called line.
- 65 70 75 80 85 90 95
9. In an automatic telephone system having a three digit final connecting group, the combination of a group of trunks, a set of first intermediate lines divided into sub-groups, means for connecting any trunk to any one of the first intermediate lines of a sub-group, a set of second intermediate lines divided into sub-groups, means for connecting any first intermediate line to a line of any one sub-group of second intermediate lines, a set of third intermediate lines divided into sub-groups, means for connecting any second intermediate line to any one of the third intermediate lines of a sub-group, a group of subscribers' lines, each subscriber's line having access to one line of each of a plurality of the sub-groups of third intermediate lines and means for initially completing two temporary circuits to establish connection between a calling line and a called line and means for establishing circuits to maintain the connection when the temporary circuits are released.

In testimony that we claim the foregoing as our invention we have signed our names this 29th day of June, 1917.

LEONARD CHARLES BYGRAVE.
THOMAS MONTAGU INMAN.
